INVENTOR.

Edgar Tregoning,
By Wilmot H. Thurston,
ATTORNEY.

UNITED STATES PATENT OFFICE.

EDGAR TREGONING, OF ATTLEBORO, MASSACHUSETTS.

ROSETTE.

No. 922,977.

Specification of Letters Patent.

Patented May 25, 1909.

Application filed November 6, 1908. Serial No. 461,296.

To all whom it may concern:

Be it known that I, EDGAR TREGONING, of Attleboro, county of Bristol, and State of Massachusetts, have invented certain new and useful Improvements in Rosettes; and I do hereby declare the following specification, taken in connection with the accompanying drawings, forming a part of the same, to be a full, clear, and exact description thereof.

My invention relates to electrical rosettes and similar electrical fittings which are adapted to support electric lamps and similar devices and in which conducting wires are connected to suitable terminals or binding-posts in the body of said rosette.

The object of the invention is to provide novel means for relieving said terminals or binding posts from any strain due to the weight of the conducting wires and depending lamp or to any undue pressure applied to the same.

Heretofore it has been customary to tie the two conducting wires together to form a knot which is located in a recess within the rosette so that any strain on the conducting wires will come on the knot instead of on the terminals. This practice of forming a knot in the conducting wires, however, is objectionable because the forming of the knot is liable to break the insulation, and the knot is also liable to pull through the central opening in the rosette.

It is the object of my invention to provide a novel form of rosette in which a very simple and efficient means for relieving the strain upon the terminals is employed. To this end my invention consists in the novel form of rosette hereinafter described and claimed, reference being had to the accompanying drawings, in which—

Figure 1 is a side elevation of my novel form of rosette, Fig. 2 is a top plan view of the same, Fig. 3 is a top plan view of the base of the rosette, Fig. 4 is a bottom plan view of the cap or cover, Fig. 5 is a vertical section on the line $x-x$, Fig. 2.

Referring to the drawings, Fig. 1 shows a usual and well-known form of rosette in which the body portion is made in two parts and comprises a base portion 1, supporting the usual main wire terminal plates 2, and a removable cap portion 3 having a central opening 4 through which extends the lamp-

cord 5 comprising the two wires 6, as shown 55 in Figs. 4 and 5.

Mounted by screws 7 in opposite sides of the cap 3 are spring-plates 8 which are constructed and adapted to engage the spring-plates 9 formed upon the inner ends of the 60 terminal plates 2, to lock the cap 3 upon the base 1 and to form an electrical connection between said cap and base. Mounted by screws 10 in opposite sides of the cap 3 are plates 11 provided with wire terminals or 65 binding posts 12 and fuse terminals 13. The bases of the spring-plates 8 are provided with extensions in which are mounted fuse terminals 14, and extending between the fuse terminals 13 and 14 in a groove 15 70 formed in the body portion of the cap 3 are fuse wires 16, all as shown in Fig. 4.

Formed integral with the body portion of the cap 3 are two upright vertical studs 17 located upon opposite sides of the central 75 opening 4 and adjacent the wire terminals 12. The ends of the wires 6 are coiled around the studs 17 and secured to the wire terminals 12, and the free ends of the studs 17 are arranged to overlie a central boss 18 80 formed upon the base 1, so that the said wires 6 will be held in place upon the studs 17 when the cap 3 is in position upon the base.

With the above construction the rosette 85 can be quickly wired up, and all the strain of the cord 5 and wires 6 will be upon the studs 17 and the terminals 12 are entirely relieved from all strain. As will be seen, the length of the studs 17 may be varied to 90 accommodate any desired number of turns of the wires 6 by simply varying the depth of the cap 3.

While I have described my invention as applied to a two-piece rosette having a base 95 and a removable cap, it will be understood that it is also adapted for use in a one-piece rosette in which the base and cap are integral.

What I claim as my invention and desire 100 to secure by Letters Patent is:

1. An article of the character described comprising a base provided with an inwardly extending boss, a removable cap provided with a central opening, two wire terminals, 105 and two strain receiving members arranged to overlie the boss formed upon said base.

2. In an article of the character described,

the combination with a base provided with a central boss, of a removable cap provided with a central opening, two wire terminals, and two vertical studs having their free ends 5 overlying the central boss upon said base.

3. An article of the character described comprising a body portion provided with a central opening two wire terminals and two vertical studs formed integral with said 10 body portion upon the interior thereof and located adjacent said wire terminals.

4. In an article of the character described, the combination, with a body portion provided with a central opening, two wire terminals and two vertical studs, of an electric lamp-cord extending through said central opening, and having its inner end portion 15 coiled around said studs and connected to said wire terminals.

20 5. In an article of the character described, the combination, with a body portion provided with a central opening, two wire terminals and two vertical studs, of an electric lamp-cord extending through said central opening and having its inner end portion 25 coiled around said studs and connected to said wire terminals, and means for holding the coils in position upon said studs.

6. In an article of the character described, 30 the combination, with a body portion comprising a base and a removable cap portion, each provided with a pair of wire terminals, and means for connecting the wire terminals upon the base portion with the wire terminals 35 upon the cap portion when said cap portion is secured to the base, of a central opening in said cap portion, two vertical studs formed upon said cap portion and an electric lamp-cord extending through said 40 central opening and having its inner end

portion coiled around said studs and connected to said wire terminals.

7. In an article of the character described, the combination, with a base portion provided with two wire terminals, of a cap portion 45 provided with a central opening, two wire terminals, an electric lamp-cord extending through said central opening and having its inner end coiled around projections formed in said cap portion and connected to the wire terminals in said cap portion, and a pair of fuse wires extending from the wire terminals in said cap portion through suitable grooves formed in the body of said cap portion to a pair of contact 50 plates adapted to engage and disengage the wire terminals upon the base portion.

8. In an article of the character described, the combination, with a base portion provided with two wire terminals and a central 55 boss, of a removable cap portion provided with a central opening, two wire terminals and two vertical studs formed integral with said cap portion and having their free ends overlying the central boss upon said base 60 portion when the cap is in position thereon, a lamp-cord extending through said central opening and having its inner end coiled around said vertical studs and connected to the wire terminals in said cap portion, and 65 a fuse wire extending from each of the wire terminals in said cap portion through suitable grooves to a pair of fuse wire terminals arranged and adapted to engage and disengage the wire terminals upon the base portion. 70

EDGAR TREGONING.
